FUSE LINK CONSTRUCTION

Ralph R. Pittman and Carroll H. Walsh,
Pine Bluff, Ark.

Application November 12, 1940, Serial No. 365,286

2 Claims. (Cl. 200—135)

This invention relates generally to protective devices for electrical circuits, and particularly to fuses used to limit to a predetermined quantity the passage of electrical energy through connected circuits.

An object of the present invention is the provision of a fuse link which fuses to interrupt the connected circuit upon passage therethrough of a definite current in a predetermined time when the predetermined time is of the order of several seconds, and which is capable of carrying, without fusing, a much higher current for fractional parts of a second.

It is well known that many existing types of fuses possess in some degree the inverse time-current characteristic stated in the above object. It is also well known that such fuses, if capable of operation on small currents, of the order of $\frac{1}{2}$ to 5 amperes, even in long periods of time, lack the surge capacity to carry for short times the high currents, of the order of hundreds of amperes, which are often imposed on overhead distribution conductors under lightning storm conditions. Such current surges are in general harmless to connected apparatus, but capable of causing fuse outages, with resulting interruption of the electricity supply.

Another object is the provision of a simple, effective and inexpensive device for the purpose described.

With these and other objects in view which will appear as the description proceeds, our invention resides in the novel construction, combination and arrangement of parts as herein-after described, and the scope of the invention will be defined in the appended claims.

In the drawing, Fig. 1 is an elevational view of the upper portion of the fuse link; Fig. 2 is an elevational view, in section, taken along the line II—II of Fig. 1; Fig. 3 is a section taken along the line III—III of Fig. 1; and Fig. 4 is an elevation view of the entire unit.

Referring in detail to the drawings, a hollow tube of conducting material 10 is provided with the upper flanged portion 11, so that it may be conveniently engaged with a terminal of the usual type of fuse link housing. An upper plug 12, of some insulating material, such as fiber, is fitted into the upper end of the container 10, and may be secured in place by crimping a portion of the container tightly against the plug around its outer surface.

A stepped recess extends downwardly through the center portion of the plug 12, coaxially with the container 10, and the button or head 17 of

the metal supporting and connecting member 16 engages the step, the member 16 extending coaxially into the tube 10 for a short distance.

Within an axially upwardly extending opening of the member 16 is secured, by pressing the respective elements together, one end of the fusible element 14, and one end of the helically formed heater coil 13. The latter two members may be formed from a nickel-chromium-iron alloy wire, this material being of a high specific electrical resistance as compared to usual materials employed for electrical conductors, such as copper or aluminum. The fusible element 14 preferably extends downwardly within the container 10 from its point of attachment to the member 16, along the axis of the container 10 and the helical coil 13, the lower end of the latter being mechanically secured and electrically connected to the container 10 by crimping at 15.

The lower end of the fusible element 14 emerges from the helical coil 13 within the container 10, and is mechanically secured and electrically connected, by crimping the respective members, to the conducting member 18, the latter extending coaxially endwise from the container 10, and loosely through a centrally located opening in the lower insulating plug 19.

A stop button 20 is crimped to the conducting member 18 in spaced relation with the outer surface of the plug 19, and arranged to engage an insulating washer 21. A compressed coil spring 22 engages at its respective ends the plug 19 and the washer 21, the arrangement being such that the spring constantly urges the conducting member 18 endwise from the tube 10, thus continuously tensioning the fusible element 14.

The electrical circuit through the fuse link is from the flanged portion 11 of the container 10 to its connection with the lower end of the helix 13 at 15, thence upwardly through the convolutions of the helix 13 to the conducting member 16, and thence downwardly through the fusible element 14 to the conducting member 18.

It may be noted that the heater coil 13, through which the fusible element 14 longitudinally extends, is not subjected to tension from the spring 22; also that the fusible element 14 is continuously tensioned by the spring 22.

The helical coil 13 and the fusible element 14, being electrically in series, and positioned as described, provide an arrangement such that the fusible element 14 operates at a higher temperature than the heater coil 13 in response to currents through the series arrangement which con-

tinue sufficiently long to obtain heating, by radiation, of the fusible element 14 by the heater coil 13. For very short-time impulses or surges of current, relatively little effect upon the fusible element 14 results from the presence of the heater 13. The arrangement therefore is one in which the fusing of the fusible element 14 is facilitated when the current continues long enough to secure radiation effects, but at the same time one which, in the absence of radiation effects attending to short-time currents, will carry substantially greater short-time currents than devices employing a single fusible element, and without the heater coil arrangement.

The operation of the device may be better indicated from a consideration of the equation—

$$\text{Temperature rise} = \frac{I^2 rt}{ms} \quad (1)$$

where temperature rise is that caused by the passage of a current I for a time t through a conductor having a resistance r , a mass m , and a specific heat s .

Noting that

$$r = \frac{kl}{a} \quad (2)$$

where

k is a constant depending upon material

l is length

a is cross-sectional area,

and substituting (2) in (1), it will be seen that temperature rise caused by a current I is directly proportional to the time the current flows, and inversely proportional to the square of the cross-sectional area, since the mass of a conductor is a direct function of both its length and area.

As t approaches zero—a condition attending the passage of surge currents through the fuse—the time is so short that the heat transmitted from the coil 13 to the fusible element 14 is negligible, and the area of the fusible element is the predominating consideration. To illustrate, substantially the same surge current will fuse identical fusible elements one of which is submerged in water, and the other of which is surrounded by a heater coil.

However, if a sufficiently large cross-sectional area is used to provide the desired surge capacity in a simple longitudinal fusible element, too much dynamic or relatively long-enduring current may be required to fuse it to make the device suitable for its intended use, since what is desired is a fuse having high surge current carrying capacity and low dynamic current carrying capacity.

To provide the latter characteristic, we arrange

the fusible element 14 so that it may be slowly heated by the coil 13 to fusion upon the occurrence of a predetermined current which, unlike a current of the character of surge-current, persists for a predetermined time. The construction is thus one which carries unusually large currents for short times of the order of a few micro-seconds, but will fuse at unusually small currents for times of the order of a few minutes.

While this invention has been described in considerable detail, it is to be understood that such description is intended as illustrative rather than limiting, as the invention may be variously embodied, and is to be interpreted as claimed.

We claim, as our invention:

1. A fuse link construction comprising a fusible element and a helically formed heater coil through which said fusible element extends, a tubular container of conducting material containing said helical coil and said fusible element, spring means associated with said fusible element and positioned externally at one end of said container, said spring means urging said fusible element in an endwise direction to withdrawal from said container, conducting means at the other end of said container electrically connecting one end of said helically formed heater coil to one end of said fusible element, and means including an insulator interposed between said conducting means and said container for fastening the joined ends of said coil and fusible element to the other end of said container.

2. A fuse link construction comprising a fusible element and a helically formed heater coil through which said fusible element extends, a tubular container of conducting material having an outwardly extending flange at one end thereof, said container containing said coil and fusible element, an insulator fastened at the flanged end of said container and provided with a centrally positioned stepped recess, conducting means having a first portion thereof resting on the step of said recess and positioned within the container beyond the outer surface of said flange and a second portion extending through said recess within said container, means mechanically fastening and electrically connecting one end of said coil and the adjacent end of said fusible element to said second portion, the other end of said coil being directly fastened and electrically connected to said container and the other end of said fusible element being connected to said container only through a series circuit arrangement of said coil and said fusible element.
